CLAIM

The ornamental design for a bumper for a vehicle, as shown and described.

DESCRIPTION

This application contains subject matter related to the following co-pending U.S. design patent applications:

Application Ser. No. 29/763,257, filed Dec. 22, 2020 and entitled “Truck Cab, Toy, and/or Replicas thereof;” and Application Ser. No. 29/763,258, filed Dec. 22, 2020 and entitled “Truck Cab, Toy, and/or Replicas thereof.”

FIG. 1 is a left, front perspective view of a first embodiment of a bumper for a vehicle according to the design;

FIG. 2 is a front view thereof;

FIG. 3 is a right side view thereof;

FIG. 4 is a top view thereof; and

FIG. 5 is a bottom view thereof.

FIG. 6 is a right, front perspective view of a second embodiment of the bumper for a vehicle according to the design;

FIG. 7 is a front view thereof;

FIG. 8 is a left side view thereof;

FIG. 9 is a top view thereof; and,

FIG. 10 is a bottom view thereof.

The dashed-dot-dashed lines represent the boundary lines of the claimed design. The broken lines in the drawings illustrate environmental subject matter only and form no part of the claimed design.
